FIG. 4.

FIG. 6.

UNITED STATES PATENT OFFICE.

JOHN BOOSH AND WASYL KOWALUK, OF CLEVELAND, OHIO.

STRINGED MUSICAL INSTRUMENT.

1,401,865.

Specification of Letters Patent. Patented Dec. 27, 1921.

Application filed July 28, 1921. Serial No. 488,099.

To all whom it may concern:

Be it known that we, JOHN BOOSH and WASYL KOWALUK, citizens of Poland, residing at Cleveland, in the county of Cuyahoga and State of Ohio, have invented certain new and useful Improvements in Stringed Musical Instruments, of which the following is a specification.

This invention relates to certain new and useful improvements in stringed musical instruments of that type adapted to be played by the manual manipulation of individual picks constantly operatively associated with each string.

15 The primary object of the present invention is to provide a stringed musical instrument of generally simplified and improved form and construction.

Another object of the invention is to provide a novel form of stringed musical instrument wherein provision is made for the arrangement of the strings so that the same are entirely incased and thereby protected from damage, with provision for permitting 25 the ready and proper escape of sound waves.

Still another object of the invention is to provide a novel arrangement of picks for the operation of the several strings of the instrument and improved means for conveniently operating said picks.

With the above general objects in view and others that will become apparent as the nature of the invention is better understood, the invention consists in the novel form, 35 combination and arrangement of parts hereinafter more fully described in connection with the accompanying drawings, in which like characters of reference indicate corresponding parts throughout the views.

40 In the drawings,

Figure 1 is a side elevational view of a stringed musical instrument constructed in accordance with the present invention,

Fig. 2 is a top plan view thereof,

45 Fig. 3 is a substantially central vertical sectional view of the same.

Fig. 4 is a horizontal sectional view taken substantially upon line IV—IV of Fig. 3 and with the pick carrying unit removed,

50 Fig. 5 is a fragmentary bottom plan view of the device shown in Fig. 1 with the bottom cover plate removed,

Fig. 6 is a fragmentary elevational view showing the mounting frame for and some 55 of the picks and actuating members thereof.

Fig. 7 is a horizontal sectional view taken substantially upon line VII—VII of Fig. 6,

Fig. 8 is a fragmentary elevational view showing a portion of one of the pick actuating members and the adjacent pick and 60 string,

Fig. 9 is a side elevational view of the device shown in Fig. 8, and

Fig. 10 is a horizontal sectional view taken upon line X—X of Fig. 9.

Referring more in detail to the several views, the present invention consists of a hollow double wall case whose inner wall 5 is of cylindrical form and whose outer wall 6 is shaped so as to give an ornamental 70 appearance preferably as shown in Figs. 1 and 3, the walls 5 and 6 being preferably provided with aligned openings which are connected by radial sound conducting tubes 7 communicating from the interior of the 75 case to the atmosphere near the top of the case, while other openings may be provided as at 8 in one or both of the walls for additional exit of the sound waves if found desirable.

The case is provided with an annular flanged string attaching plate 9 at its bottom portion of angular form in cross section so that one flange of said plate 9 flatly engages the outer surface of the bottom wall 80 10 of the case as shown clearly in Figs. 3 and 5, in which position it is rigidly fastened by means of screws 11 or the like so that the other flange of said plate 9 extends inwardly 85 of the passage through said case. This inwardly extending flange of the plate 9 is provided with a regular series of openings in which the hooked lower ends of string carrying rods 12 are engaged, said rods 12 being extended longitudinally in the passage of 90 the case toward the upper end of the latter and being of gradually increasing lengths as shown in Fig. 3. A spiral series of stringed bridge members 13 is provided upon the inner surface of the inner wall 5 so as to 100 provide recesses for the adjacent ends of the strings 14 whose lower ends are suitably attached to the upper ends of the rods 12 as by passing the same through eyes 15 provided at the upper ends of the rods and then twisting 105 said strings as shown. A suitable bottom cover 16 is nailed, glued or otherwise suitably fastened upon the bottom of the case to cover the flange plate 9 and the lower end of the case.

A plurality of string tightening screws are threaded in the upper end of the case and arranged in a circular series as at 17 in a position to have the upper ends of the 5 strings 14 attached thereto so that by turning of said screws, tightening of the strings will be had for proper tuning of the instrument, and these screws are preferably provided with exposed squared outer ends for 10 the reception of a key as at 18 as is usual in stringed musical instruments of this general character. The strings 14 and their attaching rods 12 are thus arranged in a circle and in close proximity to the inner 15 surface of the inner wall 5 of the case, and for the convenient manual actuation of the strings, a picking mechanism or unit including individual picks constantly associated with each of the strings and finger operated actuating 20 means for said picks, is secured in the upper end of the case. This mechanism or unit comprises three disks or circular plates 19, 20, and 21 rigidly connected in parallel spaced relation by means of a plurality of posts 22, 25 the plates 19 and 20 being of such diameter as to be received within the passage of the case inwardly of the strings 14 and the plate 21 being of such size as to cover or close the open upper end of the case and to rest upon 30 said end so that the same may be secured by means of screws 23 or the like rigidly in position as shown in Figs. 2 and 3, suitable grooves being provided to permit the passage of the strings between the case and 35 the plate 21 to the screws 17. Any suitable form of guide may be provided as at 24 at the upper end of the wall 5 for each of the strings 14 so as to hold the latter in spaced relation throughout from the inner surface 40 of the inner wall 5 in conjunction with the bridge pieces 13. The innermost plate 19 has a plurality of radially projecting stub shafts 25, extending toward one of the strings 14 and having a rotary pick 26 revolvably mounted thereon. Each pick 26 is 45 in the form of a disk with laterally extending cam-shaped prongs 27 upon the outer face thereof arranged in the path of the adjacent string so that as the pick is rotated a partial revolution, one of these cam teeth 50 will ride under and thereby sound said string. A push button 28 is slidably mounted transversely through the outer plate 21 directly above each pick 26 and is provided 55 with an inwardly extending push rod 29 formed with a pawl 30 at its lower end which terminates in close proximity to the adjacent pick for engagement with successive teeth 31 provided upon the rear face of said 60 pick, one tooth 31 being provided opposite each cam tooth 27, and the push button 28 and rod 29 being normally elevated by means of a spring 32 which is preferably of sheet metal form and of U-shape with its lower end fastened as at 33 to the upper surface of

the disk 20 and its upper end engaging the push button 28 in such way as to urge the same upwardly. The rods 29 are each disposed above one of the rotary picks 26 and slightly to one side of the vertical center of 70 said pick so that upon downward movement of each rod, the adjacent pick will be rotated a quarter revolution for producing a single operation of the associated string and so as to bring another tooth 31 in position 75 to be engaged by its pawl 30 when again operated as well as to bring another cam tooth 27 in position to move past the adjacent string when said pick is again so operated. The disk 20 is preferably provided 80 with transverse grooves in its edge for slideable reception of the rods 29, and a band or ring 34 is secured about the edge of said disk 20 so as to confine said rods 29 in said grooves and thereby maintain the rods 29 85 with their lower ends in proper relation to the teeth 31 of the picks 26.

In operation, the various strings are properly tuned in the usual way by sounding the same as the screws 17 are adjusted. As 90 the various strings are tuned to conform with the different notes of the octave or several octaves, a desired tune may be played by the proper successive actuation of the one or more of said strings by the depression of the 95 push buttons 28, each of which when depressed will be immediately returned to normal position when released by its spring 32 and each will when moving inwardly partially rotate its pick 26 for causing engagement of one of the pick teeth 27 with the adjacent string to sound the same. Any suitable means may be provided upon the plate 21 to denote the character of the adjacent string if necessary and it will thus be 100 seen that a useful musical instrument is provided, the playing of which incurs little experience and skill. Also, the instrument is preferably constructed of such size as to 105 rest upon the floor with the push buttons 28 110 within convenient reach of a person seated adjacent the same.

From the foregoing description, it is believed that the construction and operation as well as the advantages of the present invention will be readily understood and appreciated by those skilled in the art. Minor changes may be made without departing from the spirit and scope of the invention as claimed. 115

What is claimed as new is:

1. A stringed musical instrument including a substantially cylindrical hollow case having a circular series of longitudinally extending strings mounted therein adjacent the inner surface of the same, and manually operable means within one end of said case including finger operated members arranged in a circular series inwardly of said strings for sounding the latter. 125 130

2. A stringed musical instrument including a substantially cylindrical hollow case having a circular series of longitudinally extending strings mounted therein adjacent the inner surface of the same, and manually operable means within one end of said case including finger operated members arranged in a circular series inwardly of said strings for sounding the latter, said last named means comprising a plurality of revolute pick elements each arranged adjacent one of said strings and operatively connected to the finger actuated members.
3. A stringed musical instrument including a substantially cylindrical hollow case having a circular series of longitudinally extending strings mounted therein adjacent the inner surface of the same, and manually operable means within one end of said case including finger operated members arranged in a circular series inwardly of said strings for sounding the latter, said last named means comprising a plurality of revolute pick elements each arranged adjacent one of said strings and operatively connected to the finger actuated members, said pick elements each comprising a disk with a series of laterally extending string engaging cam teeth and laterally extending actuating teeth, and said finger actuated members having pawls disposed to engage the last named teeth of the adjacent pick element so as to impart a partial rotation to said pick element upon each inward movement of the finger operated member.
4. In a stringed musical instrument wherein a plurality of strings are provided in a circular series and in parallel relation, means for the actuation of said strings comprising a pick carrying unit embodying a frame with a plurality of radially extending stub shafts, picks of disk form journaled upon said shafts and having outwardly directed cam teeth in position to engage said strings, a plurality of inwardly projecting operating teeth carried by said picks, a plurality of finger operated longitudinally slidable pawl carrying elements disposed in said frame for movement in a direction at right angles to the axes of said picks, said pawls being disposed to successively engage the operating teeth for imparting a partial revolution to the picks upon each inward movement of the operating members, and means to yieldingly return said operating members to an inoperative position upon being released after each actuation of the picks.
5. A stringed musical instrument including a substantially cylindrical hollow case having a circular series of longitudinally extending strings mounted therein adjacent the inner surface of the same and manually operable means within one end of said case including finger operated members arranged in a circular series inwardly of said strings for sounding the latter, said last named means comprising a plurality of revolute pick elements each arranged adjacent one of said strings and operatively connected to the finger actuated members, said case being of double walled construction with sound conducting means extending through said walls.
6. In a stringed musical instrument, a case comprising a pair of walls concentrically arranged in spaced relation, the inner walls being of cylindrical form, a plurality of rods within said case inwardly of said inner wall and extending longitudinally of the case partially through the same, a flanged disk secured to the bottom of the case and having the lower ends of said rods anchored thereto, the upper ends of the rods terminating at various distances from the upper end of the case, a spiral series of bridges fixed upon the inner surface of said inner wall above the upper ends of said rods, strings extending longitudinally of the case over said bridges and attached to the upper ends of said rods, means at the upper end of the case for tightening said strings to tune the same and means within the upper end of the case and including finger actuated push buttons for the manual sounding of said strings.

In testimony whereof we affix our signatures.

JOHN BOOSH.
WASYL KOWALUK.
